United States Patent Office

Des. 189,183
Patented Nov. 8, 1960

189,183

CHAIR

John A. Kapel, Los Gatos, Calif., assignor to Glenn of California, Arcadia, Calif., a corporation of California

Filed Nov. 9, 1959, Ser. No. 58,275

Term of patent 14 years

(Cl. D15—1)

I claim:

The ornamental design for a chair, substantially as shown.
